(57) **CLAIM**

The ornamental design for a sound bar, as shown and described.

DESCRIPTION

FIG. 1 is a front perspective view of a sound bar showing our new design;

FIG. 2 is a rear perspective view thereof;

FIG. 3 is a left side view thereof, the right side being a mirror image thereof;

FIG. 4 is a front view thereof;

FIG. 5 is a top view thereof;

FIG. 6 is a rear view thereof; and,

FIG. 7 is a bottom view thereof.

The broken lines illustrate structure or features which form no part of the claimed design.

The line shading represents surface contour no ornamentation or pattern. The dot shading represents contrast, not any particular pattern.
